UNITED STATES PATENT OFFICE

124,600

DESIGN FOR A SHOE

Robert S. Cook, Fayetteville, N. Y.

Application October 18, 1940, Serial No. 95,921

Term of patent 7 years

To all whom it may concern:

Be it known that I, Robert S. Cook, a citizen of the United States and resident of Fayetteville, in the county of Onondaga and State of New York, have invented a new, original, and ornamental Design for Shoes, of which the following is a specification, reference being had to the accompanying drawing, forming part thereof.

Fig. 1 is a perspective view of a right-foot shoe embodying the invention and looking at the shoe from the right-hand or outer side.

Fig. 2 is a perspective view of the shoe looking at it from the left-hand or inner side.

The stippling on the drawing indicates a rough surface such as that presented by suede leather; the narrow strip shown between the sole and the upper is of a color contrasting to that of the upper and the sole.

I claim:

The ornamental design for a shoe, substantially as shown and described.

ROBERT S. COOK.
